Primary Examiner — Angela J Lee(74) *Attorney, Agent, or Firm* — Bacon & Thomas, PLLC(57) **CLAIM**

The ornamental design for a socket for plug, as shown and described.

DESCRIPTION

FIG. 1 is a perspective view of a socket for plug embodying my new design;

FIG. 2 is a front view of thereof;

FIG. 3 is a rear view thereof;

FIG. 4 is a top plan view thereof;

FIG. 5 is a right side view thereof;

FIG. 6 is a sectional view along 6—6 thereof;

FIG. 7 is a sectional view along 7—7 thereof;

FIG. 8 is a perspective view in state of cover being closed thereof;

FIG. 9 is a front view in state of cover being closed thereof;

FIG. 10 is a top plan view in state of cover being closed thereof;

FIG. 11 is a perspective view in state of cover being en route to be opened or closed thereof; and,

FIG. 12 is a referential view showing use state thereof.

The environment and portions of the socket for plug shown in broken lines form no part of the claimed design.
